inventor in these Letters Patent and making part of the same
To all whom it may concern.

I, James Albr. of Elizabethtown in the county of Essex and State
of New Jersey, have invented or produced a new design or figure to be
printed on fabrics which when thus printed are termed floor oil
cloths.
I do hereby declare that the accompanying drawing which is
in of trunks of trees and Landscapes, is a full and exact representation
of the same not confining myself to size or color. What I claim as
my invention and desire to secure by letters patent is the representation of trunks
and landscape as in the accompanying drawing for a design for floor oil cloth.
